UNITED STATES PATENT OFFICE.

THOMAS A. DE VILBISS, OF TOLEDO, OHIO.

DESIGN FOR A MEMBER FOR SPECULA.

SPECIFICATION forming part of Design No. 31,840, dated November 14, 1899.

Application filed October 12, 1899. Serial No. 733,439. Term of patent 7 years.

To all whom it may concern:

Be it known that I, THOMAS A. DE VILBISS, a citizen of the United States, residing at Toledo, in the county of Lucas and State of Ohio, have invented and produced a new and original Design for a Member of a Speculum; and I do declare the following to be a full, clear, and exact description of the same, reference being had to the accompanying drawings, forming a part thereof.

This invention relates to the form or configuration of one member of a certain surgical instrument usually known as a "speculum," and it consists in the novel shape of parts of that member.

The design is shown in the drawings attached hereto and forming part of this specification, and whereof—

Figure 1 is a perspective view of the member, and Fig. 2 is a vertical section.

The member comprises two parts A and B, standing substantially at right angles to each other. The part A is grooved throughout its length from its outer end, which is dished, as shown at α , to its inner end, whereat the sides terminate in angles α α , and the part B is

also grooved from its upper end, where the bottom of its grooved portion merges into that of the part A, to near its lower end. At the latter extremity is formed through the part B an open eye C, which consists of extensions of the sides b of the upright member, and the bottom of its grooved portion is turned outward, as at b b , at the top of the eye into a lip extending about parallel with the member A. D designates a hollow boss located above said lip and projecting outward from the grooved portion of the member B beneath and parallel with the member A, and the bore of this boss is threaded, as shown.

Having thus described my invention, what I claim as new and as constituting my Design Patent is—

The design for a member of a speculum, substantially as herein shown and described.

In testimony whereof I have hereunto subscribed my signature this the 7th day of October, A. D. 1899.

THOMAS A. DE VILBISS.
